[57] CLAIM

The ornamental design for a hand held spray, as shown and described.

DESCRIPTION

FIG. 1 is a perspective view of a hand held spray showing our new design;

FIG. 2 is a top plan view thereof on an enlarged scale; FIG. 3 is a front elevational view therof on an enlarged scale;

FIG. 4 is a left side elevational view thereof on an enlarged scale, the right side being a mirror image;

FIG. 5 is a rear elevational view thereof on an enlarged scale;

FIG. 6 is a perspective view of a second embodiment thereof;

FIG. 7 is a top plan view thereof on an enlarged scale; FIG. 8 is a front elevational view thereof on an enlarged scale;

FIG. 9 is a left side elevational view thereof on an enlarged scale, the right side being a mirror image; and

FIG. 10 is a rear elevational view thereof on an enlarged scale.

The broken lines shown in FIGS. 1 and 6 are for illustrative purposes only and form no part of the design.

The rectangular apertures on the spray heads of FIGS. 3 and 8 are partially shown for convenience of illustration.
